UNITED STATES PATENT OFFICE

CHESTER EVERETS HOWELL, JR., OF ORANGE, NEW JERSEY, ASSIGNOR TO F. M. HOWELL & CO., OF ELMIRA, NEW YORK

FOLDING BOX

Application filed December 31, 1930. Serial No. 505,948.

This invention relates to folding boxes; and more particularly, those formed from a single blank.

The prime object of my invention is to 5 produce a box having sides, top and bottom and a closure flap, all formed from a single blank.

Another object is to provide means in such 10 a box whereby the contents may be readily dispensed by way of a thumb slide formed in one of the faces.

Other objects will be disclosed in the specification and claims forming a part hereof.

15 In the drawing:

Figure 1 is a plan of the blank;

Figure 2 is a perspective showing the box partly assembled; and

20 Figure 3 is a perspective showing the box in assembled position.

Referring to the drawing in which like parts are designated by similar numerals:

Numeral 4 designates a front flap having an elongated thumb slide 5 formed therein 25 and a sight opening 6 in the form of a circle and a notch 7. A bottom flap 8 is separated by score lines 9 and 10 from the front flap 4 and back flap 11. A tab 12 extends from the back flap 11 and is adapted to be secured to a top flap 13.

Extending from the front flap 4 and separated by score lines 14 and 15 from the front flap 4 and a reinforcing flap 16 is formed a side flap 17. Extending from the reinforcing flap 16 and formed by score lines 18 and 19 is formed side flap 20. Extending from the side flap 20 is a closure member 21 having a notch 22 formed therein to coincide with the elongated thumb slide 5.

40 As actually used, the blank will be folded along score lines 14 and 15 to form side flap 17 and along score lines 9 and 10 to form a bottom flap 8. The reinforcing flap 16 will then be folded to coincide with the front flap 4 and the side flap 20 folded along lines 18 and 19 so that closure member 21 45 may be inserted under the front flap 4. The back flap 11 will then be folded over the reinforcing flap 16, the tab 12 being folded under the top flap 13 and secured in place.

This presents a box which may easily be collapsed by removing the closure member 21 from under the front flap 4 and the reinforcing flap 16 pushed inwardly so that 55 side flap 17 will collapse. The top 13 and

bottom 8 will likewise fold so as to present a collapsed box which may be reassembled by pulling outwardly on the reinforcing flap 16 which will tend to assemble the box.

Cigars or other merchandise may be placed 60 in the box and the brand or variety shown through the sight opening 6 and dispensed by the purchaser inserting his thumb through the thumb slide 5 and moving the cigars or other merchandise toward the point of delivery, which in this instance is closure member 21. The closure member 21 may be very 65 readily opened due to the notch 7 formed in the front flap 4, which permits the user to place his thumb in contact with the closure 70 member 21.

It is obvious that a very similar box can be formed by folding the back flap 11 on the inside of reinforcing flap 16, which disclosure comes within the scope of my invention. 75

What I claim is:

1. A blank for a foldable box comprising a front face, a flap extending from one side of the front face, said flap foldable to form the sides, a reinforcing flap and a closure 80 member, a second flap extending from an end of the front face foldable to form a bottom and back and having a securing tab on its end, said front face having a securing tab adapted to contact with the last mentioned 85 securing tab to form an end of the box, said reinforcing flap adapted to form means to permit the front face, ends and back to collapse when empty upon said reinforcing flap being pushed. 90

2. A foldable box comprising a front, top, bottom and back member formed from a single piece of material, a flap extending from one end of said box and upon being folded adapted to form the sides, a reinforcing member 95 and a closure member, the reinforcing flap adapted to form means to permit the top, bottom and back to collapse when the box is empty upon the reinforcing flap being pushed. 100

In testimony whereof I affix my signature.
